United States Patent Office.

L. K. HAWES, OF WHITEWATER, WISCONSIN.

Letters Patent No. 76,077, dated March 31, 1868.

IMPROVED BED-BOTTOM.

The Schedule referred to in these Letters Patent and making part of the same.

TO ALL WHOM IT MAY CONCERN:

Be it known that I, L. K. HAWES, of Whitewater, county of Walworth, and State of Wisconsin, have invented a new and useful Improvement in Bed-Bottoms; and I do hereby declare that the following is a full, clear, and exact description thereof, which will enable those skilled in the art to make and use the same, reference being had to the accompanying drawing, forming part of this specification, in which—

Figure 1 is a view of a portion of a bed-slat and the fastening which secures it to the bedstead.

Figure 2, a view of same, bottom side up.

Figure 3, a bar, serrated on its under side, which, with screws, forms a clamp to secure the end of an elastic strap to the slat.

Similar letters of reference in each of the figures indicate corresponding parts.

The object of my invention is to produce a superior spring-bed bottom.

A, a bed-bottom slat; B, an elastic strap, one end secured to the slat A; C, a bent staple, to which one end of the strap B is secured; D, a serrated bar, with holes in its ends for screws, which secure one end of the elastic strap B to the slat A; E, a button, to hold the staple C firmly in place; F, a portion of a bedstead.

Operation.

The slat A, having the strap B secured to it by the clamp D, and the other end of the strap B secured to staple C, as shown, the staple C is inserted in holes in the bedstead, and the button E turned, so that one end of it shall be over the end of strap B, as shown, (fig. 1.) The other end of slat A secured to the other end of the bedstead in same way, and, when a sufficient number of these slats are in position, a bed-bottom is formed. To take the slats out, turn button E back, and lift the staple C out of the holes in the bedstead.

What I claim as my invention, and desire to secure by Letters Patent, is—

1. Slat A, elastic strap B, bent staple C, and clamp D in combination, substantially as described.
2. I claim securing strap B to slat A by the serrated clamp D, substantially as described.
3. Staple C, with button E, in combination, substantially as described.

L. K. HAWES.
